UNITED STATES PATENT OFFICE.

WILLIAM WALTER HARRIS, OF MONTREAL, QUEBEC, CANADA.

METALLIC RAILWAY-TIE.

1,101,796.

Specification of Letters Patent. Patented June 30, 1914.

Application filed November 3, 1913. Serial No. 798,975.

To all whom it may concern:

Be it known that I, WILLIAM WALTER HARRIS, a subject of the King of Great Britain, residing at Montreal, in the Province of Quebec and Dominion of Canada, have invented certain new and useful Improvements in Metallic Railway-Ties; and I do hereby declare the following to be a full, clear, and exact description of the invention, such as will enable others skilled in the art to which it appertains to make and use the same.

This invention relates to railway ties, and has for its object to produce a metallic tie which will be comparatively inexpensive to manufacture, will be efficient in action, and one which may be firmly secured in the road bed.

With these and other objects in view, the invention consists in the novel details of construction, and combinations of parts more fully hereinafter disclosed and particularly pointed out in the claims.

Referring to the accompanying drawings forming a part of this specification, and in which like numerals designate like parts in all the views: Figure 1 is a diagrammatic elevational view of a tie made in accordance with my invention; Fig. 2 is a plan view of one of the members of the tie shown in Fig. 1; Fig. 3 is a sectional view of the parts shown in Fig. 2; Fig. 4 is a sectional view of the parts shown in Fig. 3, but taken on a plane at right angles to that on which Fig. 3 is taken; Fig. 5 is a detail view of the outer casing; Fig. 6 is a detail view of a modified form of the inner member; and, Fig. 7 is a perspective view of a tool useful for embedding the tie in the material of the road bed.

I indicates the rails; 2, an inner cylindrical member to which a rail 1 may be secured, as by means of the pieces 3 and bolts 4 taking against the flanges 5 of the member 2. The member 2 is provided with the inclined plates 6 and 7, fitting the interior of the outer cylinder 8 which is provided with the depending lugs 9 and 10 against which the said plates 7 and 6 respectively take. The outer cylinder 8 is preferably roughened on its bottom, as at 12, in order to enable it to more easily seat itself in the material of the road bed when said cylinder 8 is oscillated around its vertical axis, as will be more fully disclosed below.

13 represents a tie bar secured to the in-

ner cylinder 2 as by means of the clamping member 15 and the bolts 14 taking against the flange 5 of the inner cylinder 2. It will be understood, of course, that the cylinders 2 and 8 are in duplicate, that they are placed a distance apart equal to that between a pair of rails 1, and that the tie bar 13 extends between duplicate pairs.

20 represents a tool provided with a curved head 21 which is adapted to take against the inner cylinder 2, and have its member 22 fit between the pairs of lugs 9, illustrated in Fig. 2, so that upon rapidly moving the handle end of the said tool 20 to and fro, the said inner cylinder 2 and outer cylinder 8 will be oscillated in the material of the road bed. This oscillating motion will cause the ragged edges 12 of the outer cylinder 8 to firmly embed the latter in the road bed, while the inclined plates 6 and 7 of the inner cylinder will likewise move downward into said material, packing the material as they go, and firmly tamping it, so that the entire tie member will be firmly secured in the road bed. Further, upon rotating the outer cylinder 9 and embedding it into the road bed, the lugs 9 and 10 are jammed against the plates 6 and 7, which are supported from below by the earthy material caught thereunder, and the whole is bound together.

In order to insure the inner cylinder turning with the outer cylinder and also to more firmly secure the parts together, the outer cylinder 8 (see Figs. 2 and 5), is provided with oppositely disposed lugs 30 and 35, each having a lower shoulder 31 and an upper shoulder 32. The upper edge of the inclined plate 6 fits against the upper shoulder 32 of the lug 30, and its lower edge will fit against the shoulder 31 on the oppositely disposed lug 35, as will be clear from Figs. 2, 4 and 5. In the same way, the lower edge of the plate 7 will fit against the lower shoulder 31 on the lug 30, and its upper edge will fit against the upper shoulder 32 on the lug 35. The extreme edges of the plates being separated as at 36 in Fig. 2, the middle portion of each lug 30 and 35 projects between the said separated edges and compels the inner cylinder 2 to oscillate with the outer cylinder 8. The clamping members 3 and 15 and the bolts 4 and 14 firmly hold the rail 1 to the inner and outer cylinders, and the tie members 13 further brace the pair of rails.

In the modification shown in Fig. 6, the structure of the inner cylinder is the same as in the preceding figures, but instead of providing two inclined plates 6 and 7, I have 5 provided only a single plate 40 which extends almost 360° around the inner cylinder 2. This said cylinder is conveniently provided with a spiral groove to accommodate the said plate 40, but of course any other 10 suitable means may be employed for securing the parts together. When employing this modification, of course, one of the lugs 30 or 35 may be dispensed with.

In all the forms I prefer to make the bolts 15 4 and 14 square in cross section and to fit them to rectangular holes in the parts 3, 13 and 15, as indicated in dotted lines, Fig. 2. Also, I prefer to place the rails 1 slightly off the center of the cylinders as shown in Fig. 20 3, in order that a slight upward pressure may be exerted on the tie bars 13, and thereby more firmly bind the parts together.

It is obvious that those skilled in the art 25 may vary the details of construction, as well as the arrangement of parts without departing from the spirit of my invention, and therefore I do not wish to be limited to the above disclosure except as may be required by the claims.

30 What I claim is:—

1. In a railroad tie the combination of an outer member; an inner member adapted to oscillate with said outer member and provided with inclined means adapted to compact 35 the earth when oscillated; and means carried by said inner member to facilitate the securing of a rail thereto, substantially as described.

2. In a railroad tie the combination of an 40 outer cylinder; an inner cylinder coacting with said outer cylinder; and an inclined plate extending between said inner and outer cylinders, substantially as described.

3. In a railroad tie the combination of an 45 outer cylinder provided with a lug; an inner cylinder coacting with said outer cylinder; and an inclined plate rigid with said inner cylinder extending between said inner and outer cylinders and adapted to rest on 50 the under-side of said lug, substantially as described.

4. In a railroad tie the combination of an outer cylinder adapted to be oscillated; an inner cylinder provided with an inclined 55 plate located inside said outer cylinder; a lug on said outer cylinder contacting with said plate; and means carried by said inner cylinder to facilitate the securing of a rail thereto, substantially as described.

5. In a railroad tie the combination of an 60 outer cylinder having a roughened lower edge adapted to be oscillated; an inner cylinder provided with an inclined plate located inside said outer cylinder; a plurality of lugs on said outer cylinder contacting 65 with said plate and compelling said plate and inner cylinder to oscillate with said outer cylinder; and means carried by said inner cylinder to facilitate the securing of a rail thereto, substantially as described. 70

6. In a railroad tie the combination of a pair of outer cylinders on which rails are adapted to rest; an inner cylinder associated with each outer cylinder provided with means for facilitating a firm hold in the 75 material of the road bed; and a tie bar between said inner cylinders, substantially as described.

7. In a railroad tie the combination of a pair of outer cylinders on which rails are 80 adapted to rest; an inner cylinder associated with each outer cylinder provided with means comprising an inclined plate for facilitating a firm hold in the material of the road bed; a tie bar between said inner 85 cylinders; means on said inner cylinders for facilitating the securing of a tie bar thereto; and means for securing said tie bar to said inner cylinders, substantially as described. 90

8. In a railroad tie the combination of a pair of outer cylinders adapted to be oscillated; lugs on the interior of said outer cylinders; an inner cylinder located inside each outer cylinder; an inclined plate carried by 95 each inner cylinder adapted to contact with said lugs and to oscillate therewith; a tie bar extending between said inner cylinders; and means to secure said bar to said inner cylinders, substantially as described. 100

9. In a railroad tie the combination of a pair of outer cylinders provided with serrated edges adapted to be oscillated; lugs on the interior of said outer cylinders; an inner cylinder located inside each outer cylinder; a pair of inclined plates carried by each inner cylinder adapted to contact with said lugs and to oscillate therewith; a tie bar extending between said inner cylinders; and means to secure said bar to said inner cylinders, substantially as described. 110

In testimony whereof I affix my signature, in presence of two witnesses.

WILLIAM WALTER HARRIS.
